DESIGN FOR A WATER CLOSET

John R. Morgan, Oak Park, Ill., assignor to Sears,
Roebuck and Co., Chicago, Ill., a corporation of
New York

Application March 27, 1939, Serial No. 83,856

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Water Closet, of which the follow-
ing is a specification, reference being had to the
accompanying drawing, forming a part thereof.

Fig. 1 is a perspective view of a water closet
embodying my new design.

Fig. 2 is a side elevation of the same on a some-
what larger scale.

Fig. 3 is a sectional view taken as indicated
by the line 3—3 in Fig. 2.

I claim:

The ornamental design for a water closet, sub-
stantially as shown.

JOHN R. MORGAN.
